DESIGN FOR A SLIP

Harry Cohen, New York, N. Y.

Application February 8, 1937, Serial No. 67,506

Term of patent 3½ years

To all whom it may concern:

Be it known that I, Harry Cohen, a citizen of the United States of America, residing in the city of New York, county of New York, and State of New York, have invented a new, original, and ornamental Design for a Slip, of which the following is a specification, reference being had to the accompanying drawing, forming part thereof,

Fig. 1 is a front view of a slip showing my new design.

Fig. 2 is a rear view of the slip shown in Fig. 1.

I claim:

The ornamental design for a slip, substantially as shown.

HARRY COHEN.
